Primary Examiner — Susan Moon Lee(74) *Attorney, Agent, or Firm* — Harris, Shelton, Hanover & Walsh; Susan B Fentress(57) **CLAIM**

The ornamental design for a chain with pendant glasses, as shown and described.

DESCRIPTION

FIG. 1 is an isometric view of a chain with pendant glasses showing our new design;

FIG. 2 is a front view thereof;

FIG. 3 is a right side elevational view thereof;

FIG. 4 is a rear view thereof;

FIG. 5 is a left side elevational view thereof;

FIG. 6 is a top view thereof; and,

FIG. 7 is a bottom view thereof.

The chain upon which the pendant glasses hang is shown with a symbolic break in its length. The appearance of any portion of the article between the break lines forms no part of the claimed design.
